Primary Examiner — Caron D Veynar*Assistant Examiner* — Mehri Bajoul(74) *Attorney, Agent, or Firm* — McAndrews, Held & Malloy, Ltd.(57) **CLAIM**

The ornamental design for a table, as shown and described.

DESCRIPTION

FIG. 1 is a front perspective view of a table showing our new design;

FIG. 2 is a right side elevation view thereof; the left side elevation view being a mirror image thereof;

FIG. 3 is a front elevation view thereof; the rear elevation view being a mirror image thereof; and,

FIG. 4 is a top plan view thereof.

Views of the table not shown in the figures form no part of the claimed design.
